UNITED STATES PATENT OFFICE.

DELPHIN H. SPICER, OF CLEVELAND, OHIO, ASSIGNOR TO THE DYER COMPANY, OF CLEVELAND, OHIO, A CORPORATION OF OHIO.

BEET-SLICING MACHINE.

Application filed February 6, 1922. Serial No. 534,321.

To all whom it may concern:

Be it known that I, DELPHIN H. SPICER, a citizen of the United States, and a resident of Cleveland, county of Cuyahoga, and 5 State of Ohio, have invented a new and useful Improvement in Beet-Slicing Machines, of which the following is a specification, the principle of the invention being herein explained and the best mode in which I have 10 contemplated applying that principle, so as to distinguish it from other inventions.

The subject of the present invention is a slicing machine particularly adapted to the slicing of beets for use in the obtaining of 15 beet sugar. In slicing beets for sugar making purposes it is desirable to obtain uniform slices both as to thickness and section and the present machine is adapted to slice rapidly and evenly, provision being made 20 for adjusting the knives to regulate the cut and to make successive cuts positive. Provision is also made for positively holding 25 the beets against the cutting edges, instead of depending upon merely the weight of the beet as in previous machines, as when this is done, the beets tend to turn slightly under 30 the action of the knife with the result that the beginning of the cut is thicker than the end.

Other means are provided whereby the 35 knives may be removed for sharpening or because of breakage and blind boxes inserted in their places during the cutting operation so that the machine may be continuously operated although at a reduced capacity. To the accomplishment of the foregoing and related ends, said invention, then, 40 consists of the means hereinafter fully described and particularly pointed out in the claims.

The annexed drawings and the following 45 description set forth in detail certain mechanism embodying the invention, such disclosed means constituting, however, but one of various mechanical forms in which the principle of the invention may be used.

In said annexed drawings:—

Fig. 1 is a central vertical section through 50 the present machine; Fig. 2 is a composite view showing a partial plan view of the machine with sectors A, B, and C in section as shown by lines B—B, C—C, and D—D of Fig. 1 respectively; Fig. 3 is an elevational view of the hoisting winch; Fig. 4 is a plan 55 view of the hoisting winch; Fig. 5 is a sec-

tional view of the knife holding and adjusting means showing various knife and box positions; Fig. 6 is a section through the knife and blind boxes showing the vertical adjusting means for setting the position of 60 the knife box and knife; Fig. 7 is a sectional view on the line 7—7, Fig. 6, showing the limit stop for the blind box; and Fig. 8 is an interior elevation of the knife boxes and 65 knives.

As best shown in Figs. 1 and 2 the present machine is supported on a frame work of metal members 1, the machine comprising a base or bed plate 3 having a series of spaced guides 4 secured to its outer periphery by 70 means of bolts 5 or the like. At spaced points about the base the guides 4 are provided with radially extending lugs 6 adapted to rest on the members 1 and be secured thereto by suitable bolts 7 to form a rigid 75 device.

The bed plate has a central aperture 8 provided with a bushing 9 for a vertical spindle 10, ball bearings 11 being preferably employed in the bushing. This spindle is 80 supported in a second bearing base 12 by both annular and thrust bearings 13 and 14. This spindle is provided with a bevel gear 15 in mesh with a bevel pinion 16 mounted on a horizontal shaft 17 carried in suitable bearings 18. This shaft 17 is adapted 85 to be driven from any suitable power source being provided, as here shown, with tight and loose pulleys 19 and 20.

As best shown in Fig. 2, the guides 4 extend vertically and are provided with grooves in their sides to slidably receive the knife boxes 21 and the blind boxes 22. The grooves 23 in one side of the guides are deep and at points are cut through to the outside 90 of the box to form openings 24 to receive adjustable spools 25 carried on adjusting screws 26 mounted in plates 27, the screws having a bearing 28 in the guide. The grooves for the knife boxes and the boxes 95 are so arranged that the boxes can only be inserted or removed when the knife is out of its cutting position, that is, when the spool is aligned with the guide groove and the adjustment of the knife radially is only 100 possible when the boxes are moved into their cutting level and in position in the spools thus making it impossible to remove or insert a knife except when it has been withdrawn out of its cutting position. 110

- The groove 30 on the other side of each guide has a second shallower groove 31 to receive the complementary formed side 32 of the blind box 22. When set up for operation the bed plate is provided with knife boxes between each pair of guides forming a cylindrical casing substantially closed with inwardly projecting knives. These knives 33 are removably secured to the boxes by means of set screws 34 which hold the knife rigid against the inner face of the box. The inward position of the knife and thus the depth of cut is set by moving the box inwardly of the guides by means of the spools 25 actuated by the adjusting screws 26. The knife boxes are rigidly fastened in the guides by means of set screws 35 which pass through the boxes and engage with the guides.
- These guides extend below the bed or base and between each two guides is mounted a knife box and below the knife box is mounted a blind box similar to the knife box in shape but closed and with no provision for attaching a knife. These blind boxes are furnished so that they may be moved upwardly to close the casing when it is desired to remove a knife box for any reason.
- The machine is so arranged that the only way of removing the knives and knife boxes is by raising the blind boxes which push the knife boxes upwardly from below and similarly the insertion of the knife box is necessary to move the blind box down.
- Within the casing formed by the bed plate, guides and boxes, is mounted a rotating runner 40 comprising a curved base 41 having an apertured central boss 42 adapted to be received on and secured to the driving spindle by means of a locking washer 43 and nut 44. This runner has a annular top plate 45 extending over the outer portion which is connected to and supported by a series of plates 46 which are of V shape having one curved side 47, the straight side 48 being provided with adjustable runner plates 49 adapted to be moved and positively locked so as to have their outer ends set a uniform distance from the knife edges. These plates 46 divide the runner up into a series of equal sized pockets open at both the center and the outside. The upper plate has an upstanding central flange 50 forming a mouth for the runner.
- Above the runner is mounted a cover 51 secured to the upper ends of the guides by bolts 52 and provided with a central flange 53 extending into the flange 50 and forming a spout for the beets which are to be fed into the machine. The flange 53 is provided with an annular groove 54 to receive a revoluble ring 55 of a hoisting winch.
- To facilitate the removal of the knife boxes a hoisting winch is provided consisting of the ring 55 revolubly mounted in

groove 54 of the cover flange, the ends of this ring extending radially to receive four braces or arms, the outer two 55^a extending outwardly and upwardly and the lower two 56 extending downwardly and outwardly and being pinned to vertical braces 57 which carry a roller at their lower ends adapted to roll on the flat upper surface 58 of the cover, the ring 55 and braces forming a revoluble frame work. The upper ends of the vertical braces are curved to extend outwardly to surround a rack bar 59, a roller 60 being mounted on the ends to maintain the rack bar in engagement with a gear 61 mounted on a shaft 62 extending through the braces 55 and 57. This shaft is provided with a handle 63 by which the gear may be rotated to raise and lower the rack bar.

The rack bar is provided with a downwardly extending hook 64 adapted to engage in a complementary formed socket 65 in each blind box, as best shown in Fig. 1, and by raising the rack bar the blind box may be raised forcing the knife box upwardly and out of the guides. It is of course necessary to loosen the knife box in the guides before raising the same for removal. In this way any knife and box may be removed and the opening between the guides filled simultaneously so that the machine may be continuously operated, the blind boxes being provided with a latch 66 to retain them in position when raised as well as being provided with stops 67 to hold them in their lower positions.

When the machine is in operation with the runner revolving at full speed, the beets enter through the cover flange dropping into the runner and out into the pockets where the centrifugal force causes the beets to be forced out against the knife boxes and knives, or the blind boxes. The runner carries the beets past the knives cutting off successive slices, some few of which will drop down on the inside to the bed plate where they are caught by angle plates 70 secured to the bottom of the runner and moved along angles 71 secured to the bed plate to holes 72 in the bed.

Around the entire machine is a casing 73 of sheet metal or the like supported on the frame work and formed into a hopper or chute at the bottom to catch the sliced beets as they come from the knives and the few which fall through the bed plate and direct them to any suitable point of removal.

When the machine is orginally set up the blind boxes are in position and the knife boxes are inserted from the top, the grooves in the guides being so placed that the knives are out of cutting position. When the latches of the blind boxes are released the knife boxes may be lowered to the cutting

position which is determined by seats on the blind boxes resting on plates 67 at the bottom of the guides, the height of this position of the knife boxes being adjustable 5 as the knife boxes rest on adjustable set screws 76 in the tops of the blind boxes.

After the vertical positions of the knife boxes have been set, the boxes are moved inwardly by means of the spools and adjusting screws until the desired slicing thickness is obtained. It is now that the vertical adjustment of the knife boxes may be made so each knife cutting edge will track in the previous cut so as to make the 10 slicings of even section and once this position has been determined for each knife box, the boxes may be removed and inserted without further adjustment. When the knife box is finally adjusted in both 15 directions it is locked by means of the set screws.

The present machine may be continuously operated and by substituting a definite number of blind boxes for knives may be run 20 at reduced capacity so as to balance the rest of the factory if desired. The knives are preferably formed with serrated edges adapted to cut V-shaped sections from the beets and the vertical adjustment allows the 25 knives to be set so that they track or cut in the same grooves, thus cutting similar sections and full sections. The thickness of the slices, or the depth of the cut may also be regulated and these are important 30 factors in slicing beets as losses in available sugar content increase rapidly if the slices are uneven. Other advantages are the ability to change knives and boxes while the machine is in operation and also 35 to adjust the position of the knives while the machine is running so that the machine may be continuously operated.

Other modes of applying the principle of my invention may be employed instead 40 of the one explained, change being made as regards the mechanism herein disclosed, provided the means stated by any of the

following claims or the equivalent of such stated means be employed.

I therefore particularly point out and 50 distinctly claim as my invention:—

1. In a beet slicing machine, the combination of an outer casing forming a delivery hopper, a bed plate within said casing, a rotatable driving spindle extending through and above said bed plate, a series 55 of guides secured to said plate and extending vertically, knife boxes slidably mounted in said guides, blind boxes also slidably mounted in said guides below said knife boxes, 60 knives removably secured to said knife boxes, means for adjusting said knife boxes radially to adjustably position said knives to vary the thickness of the slice, a runner mounted on said spindle and rotatable therewith, said runner having open ended pockets and being adapted to force the beets 65 outwardly against said knives by centrifugal action during rotation to slice the beets.

2. In a beet slicing machine, the combination of an outer casing forming a delivery hopper, a bed plate within said casing, a rotatable driving spindle extending through and above said bed plate, a series of guides secured to said plate and extending vertically, knife boxes slidably mounted in said guides, blind boxes also slidably mounted in said guides below said knife boxes, knives 70 removably secured to said knife boxes, means for adjusting said knife boxes radially to adjustably position said knives to vary the thickness of the slice, a runner mounted on said spindle and rotatable therewith, said runner having open ended pockets and being adapted to force the beets 75 outwardly against said knives by centrifugal action during rotation to slice the beets.

Signed by me this 31st day of January, 1922.

DELPHIN H. SPICER.
